UNITED STATES PATENT OFFICE.

EGBERT H. GOLD, OF CHICAGO, ILLINOIS.

LOW-PRESSURE STEAM-HEATING SYSTEM.

1,109,675.

Specification of Letters Patent.

Patented Sept. 8, 1914.

Application filed July 31, 1912. Serial No. 712,562.

To all whom it may concern:

Be it known that I, EGBERT H. GOLD, a citizen of the United States, residing at Chicago, in the county of Cook and State of Illinois, have invented certain new and useful Improvements in Low-Pressure Steam-Heating Systems, of which the following is a specification.

My invention relates to low pressure steam heating systems.

The invention has for a primary object to provide in a low pressure steam heating system, for example, in a heating system in which the steam circulated through the radiator is kept, at substantially atmospheric pressure by means of a thermostatically operated controlling device, certain novel arrangements and devices whereby enough steam is delivered to the thermostat to keep the same hot when the radiator is put out of service.

The invention is particularly intended to meet the requirements of heating systems used upon railway cars. A great deal of difficulty has been experienced in car heating from the freezing up of the thermostatic controller when the supply of steam is shut off from the radiator. Condensation collects in the thermostat chamber of the controller and as the thermostat is ordinarily located so as to be affected by outside temperature, this water is likely to congeal, with the result that the system is clogged and has to be thawed out before it can be put back into service. The present invention provides for introducing into the neighborhood of the thermostat just enough steam to keep the same warm, this operation taking place automatically when the radiator is cut out of service.

A further object of the invention is to provide certain improvements in the design and construction of the thermostatic controlling apparatus for low pressure heating systems of the type utilizing a jet of steam at the inlet end of the radiator for developing suction at the discharge end to accelerate the circulation through the radiator; the improvements in question consisting, among other desirable features, in the provision of means for separating the water and steam at the return end of the radiator and discharging the water without letting it come into contact with the thermostat; and further, in the provision of certain devices and

arrangements for preventing steam from being drawn from the thermostat chamber into the return end of the radiator when the supply of steam to the inlet end of the radiator is cut off.

The invention has for a further object to provide a heating system having the new and improved features and consisting of the novel constructions, arrangements and devices shown in the drawings annexed hereto and which will be hereinafter more fully described and claimed.

The invention is illustrated, in certain preferred embodiments, in the accompanying drawings, wherein—

Figure 1 is a vertical sectional view taken through the controlling apparatus constructed in accordance with the invention. Fig. 2 is a sectional view, taken on line 2—2 of Fig. 1, looking in the direction of the arrows; Figs. 3 to 6 inclusive are diagrammatic views illustrating the application of the invention to different practical situations.

Like characters of reference designate like parts in the several figures of the drawings.

Referring first to Figs. 1 and 2, 25 designates a casing formed with an internal web 26 dividing it into a thermostat chamber 27, in which is located the thermostat member 28, which is of familiar construction, and an inlet chamber 29 to which leads the steam supply pipe 30. 31 designates the inlet end of a radiator and 32 the return end of the same, both communicating with the thermostat chamber 27. 33 is a nozzle having a comparatively small bore arranged in the web 26 opposite the inlet end 31 of the radiator. The function of the nozzle is to deliver the steam in the direction of the radiator in the form of a jet. With the radiator open substantially all the steam from the nozzle enters the radiator. The jet produces a partial vacuum in the thermostat chamber which, acting upon the return end 32 of the radiator, tends to draw the medium, both water and steam, through said radiator.

The shield 33^a which extends over the thermostat 28 protects the same from the steam jet which, because of its velocity due to the comparatively small cross sectional area of the nozzle 33, passes across the chamber and into pipe 31 so long as valve 46 is open. Preferably the upper end of the casing 25 is formed with the passageway 34

which extends from a point a little beyond the nozzle to the pipe 31 and which is flared at the nozzle end.

The thermostatic member 28 is interposed between an abutment 35, on the end of an adjusting screw 36, and the extremity of the stem 37 of a valve 38 designed to close the port 39 through which the supply pipe communicates with the inlet chamber 29.

- 10 The casing is formed with a suitable port or ports for discharging the water of condensation delivered by the radiator and for maintaining communication between the return end of the radiator and the atmosphere so that air may enter the radiator when the latter is put out of service and condensation takes place. In the form of controlling apparatus shown in Figs. 1 and 2 the thermostat chamber 27 communicates with the atmosphere through the pipe 40. An additional pipe 41 is employed for discharging the water of condensation. In order to prevent the water from coming into contact with the thermostat a dam 42 is interposed 25 between the water outlet 41 and the thermostat chamber, the dam being formed preferably with the minute passageway 43 so that water will drain out of the thermostat chamber if for any reason it should be considered 30 desirable to remove the pipe 40 and plug its opening. The casing 25 is, for convenience, made with taps for two return pipes and two water outlets and the superfluous taps closed with the plugs 44, 45 (Fig. 2) in case the 35 controller is used with a single radiating circuit.

The inlet end of the radiator is provided with the shut-off valve 46. When this valve is closed the chamber 27 immediately fills 40 with steam and the thermostat expands and closes or throttles the port 39. The thermostat operates against a spring 47 which tends to hold the valve 38 open. When the steam in the chamber condenses the thermostat contracts and admits more steam. Of course 45 in the end the valve reaches a balance which admits just enough steam to keep the thermostat hot.

In Figs. 3 to 6 inclusive, I have shown 50 several different applications of the above described controlling apparatus. In Fig. 3 the controller is located within the car, 48 designating the flooring of the car and 49 the train pipe. The pipes 40 and 41 extend 55 through the flooring of the car. In Fig. 4 the arrangement is practically the same except that the controller is located under the floor of the car. In both figures I have shown, by conventional representation, a 60 thermostatic air valve 50 associated with the radiator. The construction of valves of this sort is well understood and therefore need not be described in detail. The function of this device is to break the vacuum produced 65 in the radiator when the inlet valve 46 is

closed and condensation is taking place. If some such device as this were not employed there would be danger that steam from the thermostat chamber 27 would be sucked up into the radiator through its return end 70 which is in communication with said chamber. It will be understood that if desired the branch or supply pipe 31 may be provided with any suitable form of shut-off valve. The arrangement shown in Fig. 5 is practically the same as that shown in the preceding two figures except that the outlet pipe 40 is removed and the opening in the casing closed with a plug 51, the discharge taking place entirely through the pipe 41. 75 In Fig. 6 I have shown two radiating coils or units controlled by a single controlling apparatus, these coils being designated 31^a, 32^a and 31^b, 32^b, respectively, and being provided with shut-off valves 46^a, 46^b. 80 Either or both of these coils may be put into service. In either case the steam is maintained at atmospheric pressure. 85

While I have described my invention in certain preferred embodiments, it will be 90 readily understood that I do not limit the same to the particulars shown and described as modifications will occur to those skilled in the art.

I claim:

1. In a low pressure heating system, the combination with a source of supply of high pressure steam; of a radiator; controlling apparatus comprising a chamber having an outlet, a pipe leading from said chamber to the radiator, means constituting a conduit leading from the source of supply to said chamber which terminates in position to normally deliver the inflowing steam to the pipe leading to said radiator, a thermostat in said chamber and a valve actuated by the thermostat for controlling the flow of steam through said conduit; and means for closing the pipe leading to said radiator so as to direct the inflowing steam immediately to the thermostat. 100

2. In a low pressure heating system, the combination with a source of supply of high pressure steam; of a radiator; controlling apparatus comprising a chamber, a pipe leading from said chamber to the radiator, a return pipe from the radiator to said chamber, means constituting a conduit leading from the source of supply to said chamber which terminates in position to normally 110 deliver the inflowing steam to the pipe leading to said radiator, a thermostat in said chamber and a valve actuated by the thermostat for controlling the flow of steam through said conduit; and means for closing the pipe leading to said radiator so as to direct the inflowing steam immediately to the thermostat. 120

3. In a low pressure heating system, the combination with a source of supply of high 130

- pressure steam; of a radiator; a controlling apparatus comprising a chamber, a pipe leading from said chamber to the radiator, a return pipe from the radiator to said chamber, means constituting a conduit leading from the source of supply to said chamber which terminates in a nozzle adapted to deliver the steam to the pipe leading to the radiator in the form of a jet, a thermostat 5 in said chamber and a valve actuated by the thermostat for controlling the flow of steam through said conduit; and means for closing the pipe leading to said radiator so as to direct the inflowing steam immediately to the thermostat.
4. In a low pressure heating system, the combination with a source of supply of high pressure steam; of a radiator; controlling apparatus comprising a chamber, a pipe 10 leading from said chamber to the radiator, a return pipe from the radiator to said chamber, means constituting a conduit leading from the source of supply to said chamber which terminates in position to normally 15 deliver the inflowing steam to the pipe leading to said radiator, a thermostat in said chamber and a valve actuated by the thermostat for controlling the flow of steam through said conduit; means for closing the 20 pipe leading to said radiator so as to direct the inflowing steam immediately to the thermostat, said radiator being provided 25 with a thermostatic air valve to break the vacuum when the supply is shut off and condensation takes place, for the purpose described.
5. In a low pressure heating system, the combination with a source of supply of high pressure steam; of a radiator; controlling 30 apparatus comprising a chamber, a pipe leading from said chamber to the radiator, a return pipe from said radiator to the chamber, means constituting a conduit leading 35 from the source of supply of steam to said chamber which terminates in position to normally deliver the inflowing steam to the pipe leading to said radiator, a thermostat in said chamber and a valve actuated by the thermostat for controlling the flow of steam through said conduit; means for closing the 40 pipe leading to said radiator so as to direct the inflowing steam immediately to the thermostat; and means for preventing any effective quantity of steam from entering the radiator through its return end when the 45 supply is shut off from the inlet end of the radiator.
6. In a low pressure heating system, the combination with a source of supply of high pressure steam; of a radiator; controlling 50 apparatus comprising a chamber, a pipe leading from said chamber to the radiator, a return pipe from said radiator to the chamber, means constituting a conduit leading 55 from the source of supply of steam to said chamber which terminates in position to normally deliver the inflowing steam to the pipe leading to the radiator, a thermostat in said chamber, and a valve actuated by the thermostat for controlling the flow of steam through said conduit; a water outlet pipe interposed between the return end of the radiator and said thermostat chamber, and means for closing the pipe leading to 60 said radiator so as to direct the inflowing steam immediately to the thermostat.
7. In a low pressure heating system, the combination with a source of supply of high pressure steam; of a radiator; controlling 65 apparatus comprising a chamber, a pipe leading from said chamber to the radiator, a return pipe from the radiator to the chamber terminating adjacent said thermostat, means constituting a conduit leading from the source of supply of steam to said chamber

which terminates in position to normally deliver the inflowing steam to the pipe leading to the radiator, and a valve actuated by the thermostat for controlling the flow of steam through said conduit; a water outlet 70 pipe leading from the return pipe and a dam interposed between the water outlet pipe and said thermostat.

7. In a low pressure heating system, the combination with a source of supply of high pressure steam; of a radiator; controlling apparatus comprising a chamber, a pipe leading from said chamber to the radiator, a return pipe from the radiator to said chamber, means constituting a conduit leading 75 from the source of supply to said chamber which terminates in position to normally deliver the inflowing steam to the pipe leading to said radiator, a thermostat in said chamber and a valve actuated by the thermostat for controlling the flow of steam through said conduit, and means for closing the pipe leading to said radiator so as to direct the inflowing steam immediately to the thermostat, said radiator being provided 80 with a thermostatic air valve to break the vacuum when the supply is shut off and condensation takes place, for the purpose described.

8. In a low pressure heating system, the combination with a source of supply of steam, of a radiator, means constituting a steam passageway between the source of supply and the inlet end of said radiator which said passageway has an outlet, a valve 95 to control the inflow of steam into said passageway, and a thermostat located in free communication with said passageway but out of the direct line of flow of steam from the source of supply to the radiator, and a 100 shut off valve in said passageway whereby the steam may be directed from said source of supply to said thermostat.

9. In a low pressure heating system, the combination with a source of supply of steam, of a radiator, means constituting a steam passageway between the source of supply and the inlet end of said radiator, a valve to control the in-flow of steam into 110 said passageway, a thermostat located in 115 free communication with said passageway but out of the direct line of flow of steam from the source of supply to the radiator, and a shut off valve in said passageway whereby the steam may be directed from 120 said source of supply to said thermostat, said radiator having an outlet arranged so that the medium therefrom will influence said thermostat.

10. In a low pressure heating system, the combination with a source of high pressure steam, of a radiator and a controlling apparatus comprising a casing having a partition dividing the same into a valve chamber having a port adapted to pass steam from the 125 130

1 source of supply, and a thermostat chamber, a pipe leading from the thermostat chamber to the radiator, a nozzle in said partition arranged in line with said pipe, a thermostat 5 in said thermostat chamber, a valve in the valve chamber to close the aforesaid port having a stem extending through said partition and operatively engaged by the thermostat, a shield which intervenes between the 10 steam jet from the nozzle and said thermostat, and a return pipe from the radiator to said thermostat chamber.

11. In a low pressure heating system, the combination with a source of high pressure 15 steam, of a radiator and a controlling apparatus comprising a casing having a partition dividing the same into a valve chamber having a port adapted to pass steam from the source of supply, and a thermostat chamber, 20 a pipe leading from the thermostat chamber to the radiator, a nozzle in said partition arranged in line with said pipe, a thermostat in said thermostat chamber, a valve in the valve chamber to close the aforesaid port 25 having a stem extending through said partition and operatively engaged by the thermostat, a shield which intervenes between the steam jet from the nozzle and said thermostat, a return pipe from the radiator to said

thermostat chamber, and a shutoff valve in 30 the pipe leading to the radiator.

12. In a low pressure heating system, the combination with a source of high pressure steam, of a radiator and a controlling apparatus comprising a casing having a partition 35 dividing the same into a valve chamber having a port adapted to pass steam from the source of supply, and a thermostat chamber, a pipe leading from the thermostat chamber to the radiator, a nozzle in said partition 40 arranged in line with said pipe, a thermostat in said thermostat chamber, a valve in the valve chamber to close the aforesaid port having a stem extending through said partition and operatively engaged by the thermostat, a shield which intervenes between the steam jet from the nozzle and said thermostat, a return pipe from the radiator to said 45 thermostat chamber, a pipe leading from the thermostat chamber to the atmosphere, a water outlet leading from the return pipe from the radiator, and a dam interposed between the end of said last named pipe and the thermostat.
